UNITED STATES PATENT OFFICE.

HANS ZIEGLER, OF REUTLINGEN, GERMANY.

FASTENER FOR NECKTIES.

SPECIFICATION forming part of Letters Patent No. 627,566, dated June 27, 1899.

Application filed January 31, 1899. Serial No. 704,020. (No model.)

To all whom it may concern:

Be it known that I, HANS ZIEGLER, professor, a subject of the King of Würtemberg, residing at Reutlingen, in the Kingdom of Würtemberg, German Empire, have invented a new and useful Fastener for Neckties, of which the following is a specification.

My invention relates to a fastener for neckties in combination with a collar-stud.

Various necktie-holders are made and sold; but they are useless because some of them are provided with a pointed catch, which pricks holes through and spoils the necktie, and others, without a catch, allow the necktie to slip unless it is pressed into the holder very tight. These disadvantages are removed by my invention.

In the accompanying drawings, Figure 1 represents a view of the fastener closed and provided with spiral springs; Fig. 2, a cross-section through Fig. 1; Fig. 3, a view of a modification of the fastener with closed lid and provided with flat springs, the dotted lines showing the lid open. Fig. 4 is a front view of Fig. 3; Fig. 5, an inside view of the lid; Fig. 6, a top view of the fastener with the lid removed, and Fig. 7 shows how the fastener is used.

For fastening the device to the collar, for instance, a shank *a* with double-hinged shoes is used. To this a U-shaped frame *u* is attached, which at the top of its bent-up ends is provided with a hinge *b* at one side and with a projection *c* at the other, both of which serve to fix the lid *o*. One end of the lid *o* has the hinge *b*. The other end has the shape of a hook in order to be able to catch behind the projection or rim *c* of the frame *u*. At this hooked end of the lid *o* a finger or nose *q* and a hole *p* are provided, through which latter, *p*, the lengthened end *d* of the frame *u* can pass. The parts *d* and *q* serve for raising the lid by pressing the finger-nail between them, which disengages the said frame projection from the hook.

Inside the upright sides narrow guides *f* are arranged for the purpose of guiding and fixing the moving of a plate *m*. The surface of the plate *m* is rifled. Its sides *n* are bent upward, so that the lid *o*, which is also rifled inside, can place itself between these side walls *n*, Fig. 2. These bent-up walls *n* of the slideable plate *m*, which laterally confine the lid *o*, secure a firm hold of the tie and at the same time improve its appearance, as they cause the tie to fall in folds, which is not the case with any of the existing fasteners. The movable plate *m* can be moved up and down in the frame-like guides *f* of the side walls. This plate *m* is always pressed upward by the springs *s* in Fig. 1 or *s'* in Fig. 3, located between the bases of the frame *u* and the slideable plate *m*. This slideable plate *m* catches, when pressed upward by the springs, with its ends under the upper bent-together ends of the guides *f*, and it is pressed down when the necktie is put in and pressed down by the lid *o*.

What I claim as my invention, and desire to secure by Letters Patent, is—

In a fastener for neckties the combination of a U-shaped frame *u*, having a shank and hinged shoes, guides *f* inside the U-shaped part *u* of the frame, provided with hinge *b* at one end and projection *c* at the other end and the rifled lid *o* movable on the hinge *b*, and having a catch projection *c*; with a plate *m* slideable in said frame in guides *f*, said plate rifled on its inner surface and provided with lateral bent-up walls *n* and springs arranged between the base of the frame and the slideable plate, substantially as described and for the purpose set forth.

HANS ZIEGLER.
